UNITED STATES PATENT OFFICE.

MILO SANFORD DERINGER, OF BURNSVILLE, WEST VIRGINIA, ASSIGNOR
OF ONE-HALF TO FRANKLIN W. HEFNER, JESSE A. L. HEFNER, AND
ERNEST W. HEFNER, OF BURNSVILLE, WEST VIRGINIA.

CARBURETER.

SPECIFICATION forming part of Letters Patent No. 702,637, dated June 17, 1902.

Application filed April 13, 1900. Serial No. 12,728. (No model.)

To all whom it may concern:

Be it known that I, MILO SANFORD DERINGER, a citizen of the United States, and a resident of Burnsville, in the county of Braxton and State of West Virginia, have invented a new and Improved Gas-Machine, of which the following is a full, clear, and exact description.

This invention relates to improvements in carbureters; and it consists in the novel features of construction hereinafter described, reference being had to the accompanying drawing, which illustrates one form in which I have contemplated embodying my invention, and said invention is fully set forth in the following description and claim.

Referring to the drawing, the figure is a sectional view of my improved device.

The objects of my invention are, first, to provide a device for generating gas, and, second, to so arrange the inlet and outlet openings thereof that any desired richness may be obtained in the quality of the gas.

In carrying out my invention I use a tank A of any desirable size closed at the top by the head B and provided with a suitable gage C and cock D near the lower part thereof. An air-inlet pipe a is secured in the head and extends downwardly into and to a point near the bottom of the said tank A. An outlet-pipe b is also secured in the head B and enters the said tank at the top. Both of these pipes a and b are connected with the air-inlet and mixing pipe c, the pipe a by the union a' and pipe a² and the pipe b by the union b' and pipe b². In the pipe a² is a suitable controlling-valve a³. The pipe b² is also provided with a valve b³ of like construction. Between the connecting-pipes a² and b² in the air-inlet and mixing pipe c is another valve c' of ordinary construction. Beyond the pipe a² the air-inlet and mixing pipe is provided with still another valve c² and a funnel-shaped air-inlet piece c³. A tap D' is provided in the head B, which may be removed for the purpose of supplying oil to the tank. In practice these devices are duplicated, as shown, and any number of them coupled together. In this form the air-inlet and mixing pipe c is connected up with each succeed-

ing tank in the series, as shown, or each part may be duplicated, when the four-way connection at the top of the pipe a² would be substituted for the three-way connection and the air-inlet construction, consisting of the valve c² and air-inlet piece c³, applied to each tank. I will describe the operation of the device when several of these tanks are coupled together, and it is obvious that the operation of a single tank or generator will be set forth therein.

A suction is created in the air-inlet and mixing pipe c by any suitable means after the tanks have been supplied with the requisite amount of oil and the valves c' closed. The valves b³ are left open, and the suction created through the outlet-pipes b² forms a partial vacuum in each tank above the oil. The valves a³ and c² of each tank having been left open, air passes down through the pipe a in a well-known manner, rises through the oil, and becomes charged with gas. When a number of the above-described tanks are coupled together in series and it becomes desirable to dilute the gas, the valve c' is opened slightly, when the air coming through the funnel-shaped part c³ will divide and a portion will pass downwardly through the pipe a in the first tank in series, through the oil in said tank, and emerge into the air-inlet and mixing pipe through pipe b as a gas, while a portion of said free air will pass directly through the valve c' in the air-inlet and mixing pipe and meet and mix with the gas as it emerges from pipe b, whereby said gas will be diluted. This operation is repeated in the next tank, a portion of the diluted gas passing downwardly through the inlet-pipe in said tank, through the oil and outlet-pipe into the air-inlet and mixing pipe, while a portion of the diluted gas will pass directly through the valve c' and mix with the higher-charged gas as it emerges from the second tank, and so on through the entire series. By this arrangement of devices I obtain a more perfect mixture of free air and vapor and am enabled to produce a gas of any desired richness.

What I claim, and desire to secure by Letters Patent, is—

In a gas-generator, the combination with a

series of tanks for containing hydrocarbon liquid, each provided with an inlet-pipe having a regulating-cock, and an outlet-pipe having a regulating-cock, of a single air-inlet and mixing pipe connected with the inlet and outlet pipes of all of said tanks, said air-inlet and mixing pipe having one end open to the atmosphere and provided with a series of cocks located between the connections of the air-inlet and mixing pipe with the inlet and outlet pipes of each tank, whereby a communication may be established from the air-

inlet directly through said air-inlet and mixing pipe in addition to the communication between the air-inlet and mixing pipe and said tanks, substantially as described.

In testimony whereof I have signed my name to this specification in the presence of two subscribing witnesses.

MILO SANFORD DERINGER.
